FOLDING ARMCHAIR

John Gulson Barsness, Black Earth, Wis.

Application January 28, 1950, Serial No. 141,011

1 Claim. (Cl. 155—147)

1

This invention relates to a folding armchair wherein the frame of the chair is constructed of lightweight metal tubing or the like and the seat and back are of canvas or other suitable pliable material.

One of the principal objects of the invention is to reduce the number of parts necessary for the frame construction and to simplify the construction and assembly of the parts.

Another object of the invention is to increase the combined strength and rigidity of the frame without requiring an increase in material strength of the individual elements, whereby a lightweight chair may be constructed of substantial rigidity and serviceability.

Another object is to provide a folding armchair in which the individual members reinforce each other and combine in supporting the load.

Another object is to remove torsional stress of pivotal joints in such a chair, whereby the joints may be of simple construction and of long life.

Another object is to simplify the foldability of such an armchair and to reduce the space requirements thereof when folded.

The invention is illustrated in the accompanying drawings in which:

Figure 1 is a perspective view of the chair in upright position;

Fig. 2 is a perspective view showing the chair in a partially folded position;

Fig. 3 is a perspective view showing the chair completely folded;

Fig. 4 is an enlarged detail view partially in section showing one of the pivotal joints;

Fig. 5 is an enlarged detail view partially in section showing the rear seat support member; and

Fig. 6 is a perspective view of the arm unit separate from the chair.

The chair is constituted of four tubular frame units, each embodying a single piece of metal tubing bent to provide a pair of side members connected together at one end by a cross member whereby each unit is a single piece U-shaped rigid frame in itself. In all but one instance the open ends of the units are secured to another unit near to the closed end of the latter thereby providing the rigidity of a substantially rectangular frame. And in the one instance where the open end of one unit is secured near the open end of another unit one of the open ends has its ends bent toward one another into alignment and secured rigidly in abutting relation thereby simulating a closed end.

Referring to the several frame units, the legs

of the chair comprise two cross units 1 and 2, each having their closed ends disposed downwardly to support the chair on the floor.

The rear leg unit 1 is narrower than front leg unit 2 so that the upwardly and rearwardly extending sides 3 of unit 1 pass between the upwardly and forwardly extending sides 4 of unit 2. The sides 3 are pivotally secured at 5 to the corresponding sides 4 by suitable rivet pins 6, or the like, shown in detail in Fig. 4. The pivotal connections 5 are located substantially centrally of the sides 3 and 4 so that the latter are foldable to adjacent positions, and when open take the general form of an X.

The frame unit 7 constituting the back of the chair has its closed end at the top, and its sides 8 extend downwardly to pivotally connect at 9, with the upper ends of the corresponding sides 3 of unit 1.

The upper ends of sides 3 of unit 1 are bent toward each other into alignment and abutting relation and are rigidly secured together by an insert 10 which is telescoped by the abutting tubular frame elements and secured in place by means of indentations 11 formed inwardly from the tube and into the insert, or by other suitable means.

The arm unit 12 completes the frame and has its closed end extend across the front of the seat 30 with the upper ends of sides 4 of the front leg unit 2 pivotally secured to the sides 13 just above the corresponding curved corner of the unit. The sides 13 of unit 12 extend upwardly and rearwardly from the front of the seat to an arm level and then rearwardly to back unit 7 where they are pivotally attached at 14 to the corresponding sides 8 about centrally of the height of the latter.

The seat for the chair comprises a canvas or other suitable foldable seat member 15 secured 40 upon the closed front cross member of arm unit 12 and to the closed rear cross member of rear leg unit 1.

The back for the chair comprises a canvas or other suitable member 16 extending across the upper portion of the back unit and secured around the side members 8 above the pivotal connections 14 which support the same against dropping downwardly. An additional support for back 16 may be provided in the form of the strap 17 extending over the upper closed cross member of back unit 7.

In order to retain seat member 15 substantially horizontal when the chair is open and supported upon a horizontal floor, the forward upper ends 55 of sides 4 of unit 2 are curved upwardly to meet

the corresponding side arms 12 to which they are pivotally connected by joints 18.

The chair shown may be folded readily into a compact unit as shown in Figs. 2 and 3 by moving the upper cross members to which seat 15 is secured toward each other and tilting the back unit rearwardly until it folds back against the leg units.

The framework of the chair may be constructed of any suitable lightweight material such as extruded tubing of aluminum alloy.

Various embodiments of the invention may be employed within the scope of the accompanying claim.

I claim:

In a folding armchair of tubular metal construction comprising a substantially rectangularly shaped leg unit extending upwardly and rearwardly, a generally U-shaped leg unit with the open end extending upwardly and forwardly, 20 said leg units being pivotally connected centrally of their upwardly extending sides, a back unit of generally U-shape with the open end connected to the sides of said first named leg unit somewhat forwardly and downwardly of its rear edge, 25 a generally U-shape single piece arm unit with

its open end pivotally attached to said back unit at an armrest height above the chair seat, the forward ends of the sides of said arm unit being bent downwardly to dispose the transverse cross member thereof in the approximate plane of the chair seat at the forward edge of the seat, and the open end of said second named leg unit being bent upwardly and pivotally attached to the downwardly bent sides of said arm unit slightly above and rearwardly of the transverse cross member of said arm unit.

JOHN GULSON BARSNESS.
